(57) CLAIM

The ornamental design for a dishwasher rack accessory, as shown and described.

DESCRIPTION

FIG. 1 is a front perspective view of the dishwasher rack accessory showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view of the dishwasher rack accessory in a state of use;

FIG. 9 is another perspective view showing the design in state of use with the side rack put in an upright position;

FIG. 10 is another perspective view of the dishwasher rack accessory in another state of use; and,

FIG. 11 is another perspective view of the dishwasher rack accessory in a further state of use.

The broken lines depict portions of the dishwasher rack accessory that form no part of the claimed design. All other broken lines are for the purpose of illustrating environmental structures and form no part of the claimed design.

1 Claim, 11 Drawing Sheets
